UNITED STATES PATENT OFFICE.

FREDRICK W. BISHOP, OF LOS ANGELES, CALIFORNIA.

DESIGN FOR A CASING FOR COIN-CONTROLLED APPARATUS.

SPECIFICATION forming part of Design No. 22,761, dated August 29, 1893.

Application filed July 20, 1893. Serial No. 481,057. Term of patent 7 years.

To all whom it may concern:

Be it known that I, FREDRICK W. BISHOP, a citizen of the United States, residing at Los Angeles, in the county of Los Angeles and State of California, have invented and produced a new and original Design for the Casing of a Coin-Controlled Apparatus; and I do hereby declare the following to be a full, clear, and exact description of the same, reference being had to the accompanying drawing, forming a part thereof, which represents a perspective view of the casing embodying my design.

The essential feature of the design consists in the ornamental front of the casing of the apparatus, which front is clearly shown in the accompanying drawing.

The upright frame A and base B which constitute the casing and inclose the several parts

of the apparatus, and the front of the frame is ornamented by the lines C which cross each other diagonally to form diamond-shaped figures D. The base B of the casing extends out some distance beyond the front of the frame A and has ornamental moldings E F at top and bottom respectively, and the frame A at its top has the molding G.

What I claim is—

The design for the casing of a coin controlled apparatus as herein described and shown.

In testimony whereof I affix my signature in presence of two witnesses.

FREDRICK W. BISHOP.
